(57) **CLAIM**

The ornamental design for a portable low profile flexible angle stand for electronic devices, substantially as shown and described.

DESCRIPTION

FIG. 1 is a rear perspective view of a portable low profile flexible angle stand for electronic devices;

FIG. 2 is a front perspective view thereof;

FIG. 3 is a bottom perspective view thereof;

FIG. 4 is a rear view thereof;

FIG. 5 is a front view thereof;

FIG. 6 is a right side view thereof;

FIG. 7 is a left side view thereof;

FIG. 8 is a top view thereof;

FIG. 9 is a bottom view thereof;

FIG. 10 is a side perspective view of a portable low profile flexible angle stand for electronic devices in a backward leaning position;

FIG. 11 is a side perspective view of a portable low profile flexible angle stand for electronic devices in a fully backward closed position;

FIG. 12 is a side perspective view of a portable low profile flexible angle stand for electronic devices in a forward leaning position; and,

FIG. 13 is a side perspective view of a portable low profile flexible angle stand for electronic devices in a fully forward opened position.
